TURBINE CONTROL MECHANISM

Application filed June 30, 1930. Serial No. 464,988.

My invention relates to a control mechanism for a prime mover, more particularly to a control mechanism for a multistage elastic fluid prime mover having openings at 5 two or more intermediate pressure stages for extracting partially expanded motive fluid from the prime mover or for admitting motive fluid thereto, and it has for its object to provide an improved construction of such 10 mechanism.

A more particular object is to provide a control mechanism of the character set forth which will, upon change in demand for flow of fluid through one of the openings, operate 15 the valve means at said one opening to effect the desired change in flow and to maintain the desired pressure, and which will at the same time operate the admission valve and the valve means at the other opening to maintain 20 the proper load on the prime mover and the proper flow and pressure at said other opening.

In accordance with my invention, I provide each stage having such opening a fluid pressure 25 varying in response to changes in flow or pressure at all of the openings, and a regulating mechanism responsive to said fluid pressure for controlling the flow of fluid at said stage.

The above and other objects are effected by 30 my invention, as will be apparent from the following description and claims taken in connection with the accompanying drawings, forming a part of this application, in which:

Fig. 1 is a diagrammatic view of one embodiment of the control mechanism applied to a multi-stage elastic fluid turbine;

Fig. 2 is an elevation of a detail; and,

Fig. 3 is a diagrammatic view of a modified 40 form of control mechanism.

Figures 4 to 7 inclusive are diagrammatic illustrations of the governing mechanism showing the positions of the levers for various conditions of bleeder pressure.

Referring now to the drawings more in detail, in Fig. 1, I show an elastic fluid turbine 10 having a casing 11 and a rotor 12. The turbine is supplied with motive fluid, which may be any suitable elastic fluid, such as 50 steam, from a conduit 13 and the admission

thereof to the turbine is controlled by an admission valve 14.

The turbine 10 is designed for operation in connection with demand for elastic fluid at two different pressures below the pressure 55 at which motive fluid is admitted to the turbine. For example, elastic fluid at pressures of 125 lbs. per square inch and 8 lbs. per square inch may be required, while elastic fluid may be admitted to the turbine at a 60 pressure of 400 lbs. per square inch. The expansion from the latter pressure to either of the lower pressures is utilized in the turbine to develop power.

The casing 11 is formed with an opening 65 15 at an intermediate pressure stage 15' from which elastic fluid at the higher extraction pressure may be withdrawn from the turbine to a conduit 16. It is formed with a similar opening 17 at a lower, intermediate-pressure 70 stage 17' from which elastic fluid of lower extraction pressure may be withdrawn to a conduit 18. The openings 15 and 17 divide the turbine into a high-pressure section 19, an intermediate pressure section 21 and a low-pressure section 22, the intermediate pressure stages 15' and 17' receiving partially expanded motive fluid from the discharge or low-pressure ends of the high-pressure section 19 and the intermediate pressure section 21, respectively.

A diaphragm 23 is provided between the pressure stage 15' and the section 21, and a diaphragm 24 is provided between the pressure stage 17' and the section 22. A passage 85 25 provides a by-pass around the diaphragm 23 and contains a valve 26 for controlling the flow of motive fluid to the intermediate pressure section 21. Likewise, a passage 27 provides a by-pass around the diaphragm 24, 90 and a valve 28 is interposed in the passage to control the flow of motive fluid to the low-pressure section 22.

It is the function of the valves 26 and 28 to maintain the desired pressures at the pressure stages 15' and 17', and the corresponding openings 15 and 17, by holding back from the lower stages the amount of motive fluid required for extraction. In order to maintain 95 the pressures at the extraction stages and the 100

speed of the turbine substantially constant, the action of these valves and the admission valve 14, upon changes in load and demands for extracted fluid, should be as follows:

Assume first, constant demands and flows at the openings 15 and 17, and a change in load on the turbine; for example, an increase in load. All of the valves should be moved in opening direction an amount to provide equal additional flow of motive fluid through all sections of the turbine.

Assuming constant load and constant demand at the opening 17, and an increase in demand at the opening 15, there should be an increased opening of the admission valve 14 and decreased openings of the valves 26 and 28. The increased amount of motive fluid held back by the valve 26 and the increased admission by the valve 14 provide the increased amount of extracted fluid. The valve 28 decreases the admission to the low-pressure section 22 by an amount equal to the decrease in flow through the intermediate-pressure section 21, so that the amount of fluid for extraction through the opening 17 remains the same. A portion of the power development is transferred from the intermediate-pressure section 21 and the low-pressure section 22 to the high-pressure section 19.

Assume now constant load and constant demand at the opening 15, and an increase in demand for fluid at the lower extraction pressure. The openings of the valves 14 and 25 should be increased and the opening of the valve 28 should be decreased. The increased flow through the high-pressure section 19 and the intermediate-pressure section 21 and the increased amount held back by the valve 28 provide the increased amount of fluid for extraction, and a portion of the power development of the low-pressure section 22 is transferred to the high-pressure section 19 and the intermediate-pressure section 21.

In other words, as the demand for extracted fluid increases at any one opening, the valves on the high-pressure side thereof should be moved in opening direction, while the valves on the low-pressure side thereof should be moved in closing direction.

Such operation of the valves is effected by my novel control mechanism which will now be described. The valves 14, 26 and 28 are connected to fluid pressure governors 29, 31 and 32, respectively. Each governor includes a cylinder 33, and a piston 34 operating therein and connected to the associated valve through a lever 35 pivoted to a stationary fulcrum at 36. A spring 37 biases the piston 34 in the direction for opening the associated valve.

Fluid pressure varying as the square of the speed of the turbine is developed by an impeller 38 mounted on the rotor shaft 39. It is conveyed through a conduit 41 to the cylinder 33 of each governor and imposed on the

piston 34 in opposition to the spring 37 and in the direction for closing the associated valve.

It is to be understood that any suitable form of governor may be employed, and that it may embody a fluid pressure relay mechanism. Two forms of suitable construction are shown in my Patent No. 1,778,004, granted October 7, 1930.

In order to modify the action of the several governors in accordance with the variations in demand for extracted fluid, I apply an opposing fluid pressure to the opposite side of the piston 34 of each governor, biasing the piston in valve-opening direction. This opposing pressure is derived from a restricted flow, through an orifice 42 which may be located in the piston 34, of fluid under pressure delivered by the impeller 38. The opposing pressures applied to the governors 29, 31 and 32 are controlled by pressure relief valves 43, 44 and 45, respectively, communicating with the governors through conduits 46, 47 and 48, respectively.

Each pressure relief valve is biased to closed position by a spring 49, whose compression is varied by a piston 50, operating in a cylinder 51. The piston 50 is controlled by a stem 52 extending through an opening in the piston 50 and having a slot 53. The piston 50 is moved to a given position relative to the stem 52 by means of a restricted flow of fluid pressure to the cylinder 51, supplied from a branch of the conduit 41 through an orifice 54.

The fluid pressure forces the piston 50 downwardly to compress the spring 49 until the slot 53 is uncovered sufficiently by the piston 50 to permit escape of the fluid at a rate equal to its admission through the orifice 54. Thus, by vertical movement of the stem 52, the piston 50 is moved to vary the pressure or compression of the spring 49 and the value of the opposing fluid pressure applied to the piston 34 of the associated governor.

A pressure-responsive diaphragm 55, subjected to the pressure of the fluid in the conduit 16 conveyed through a conduit 56, is pivoted to a lever 57. The latter is pivoted to a stationary fulcrum 58 and it is biased in opposition to the force of the pressure on the diaphragm 55 by a group of weights 59 and a spring 61.

A second pressure-responsive diaphragm 62, subjected to the pressure in the conduit 18 conveyed through a conduit 63, is pivoted to a lever 64. The latter is pivoted to a stationary fulcrum 65 and is biased in opposition to the force of the fluid pressure on the diaphragm 62 by a group of weights 66 and a spring 67. The springs 61 and 67 are adjustable to provide some adjustment of the pressures to be maintained in the conduits 16 and 18.

The lever 57 is pivoted at 68 to a floating lever 69. The lever 69 has three arms, the arms 71 and 72 being connected to the stems of the pressure relief valves 44 and 45, respectively. The third arm 73 is connected by means of a link 74 to an arm 75 carried by the lever 64, the connection being such that movement of the lever 64 rotates the lever 69 about the pivot 68. A floating lever 76 is connected at one end to the lever 64 and at its other end, through a link 77, to the lever 57. Intermediate its ends, it is connected to the stem of the relief valve 43, the connection including a link 78 and a lever 79, pivoted to a fulcrum 81, in order to obtain the proper direction of operation of the pressure relief valve 43.

The operation of the above-described control mechanism is as follows:

Assume first a change in load on the turbine with the extraction pressures remaining constant, providing constant opposing pressures in the governors. If the load is decreased, the speed increases, and the increased impeller pressure acts on the piston 34 of each governor to move the associated valve in closing direction. The flow to each of the sections 19, 21 and 22 is decreased by a like amount, the difference in flow between the high-pressure section and the intermediate-pressure section 21, which is supplied to the opening 15, remaining constant, and the difference between the flow through the intermediate-pressure section 21 and the low-pressure section 22, which is supplied to the opening 17, also remaining constant. Upon increase in load, the speed decreases. The resulting decreased impeller pressure permits the spring 37 of each governor to move the piston 34 in valve-opening direction. An increase in flow throughout all the sections of the turbine is provided to carry the increased load, the flow through the openings 15 and 17 remaining the same.

Assume now a condition of constant demand for extracted fluid at the lower extraction pressure, and an increase in demand for extracted fluid at the higher extraction pressure at the opening 15, the load remaining constant. The lever 64 remains stationary. The increase in demand for the higher pressure extracted fluid is accompanied by a decrease in pressure thereof, within the limited regulating range, which decrease in pressure is communicated through the conduit 56 to the diaphragm 55. The operation may be more readily understood by reference to Fig. 4, wherein the positions of the levers before the decrease in pressure are indicated in full lines, and by dotted lines after the decrease in pressure. The lever 57 is tilted in counter-clockwise direction by the spring 61 an amount determined by the effective scale of the spring. The upward movement of the right-hand end of the lever 57 raises the lever 69. The upward movement of the lever 69 is

effected without any appreciable tilting thereof about the pivot 68 by reason of the connection of the arm 73 with the arm 75 through the link 74. Both arms 71 and 72 move upwardly, therefore, moving the stems 52 of the pressure relief valves 44 and 45 upwardly with them. As heretofore explained, upward movement of the stem 52 results in decreased pressure provided by the relief valve, and the pressure relief valves 44 and 45 decrease the opposing pressures on top of the pistons 34 in the governors 31 and 32. Said pistons are thereupon moved by the impeller pressure amounts determined by the springs 37 to effect closing movements of the valves 26 and 28.

The upward movement of the right-hand end of the lever 57 also results in upward movement of the right-hand end of the floating lever 76, the left-hand end being held stationary by the lever 64. The lever 79 is tilted in clockwise direction, effecting downward movement of the stem 52 of the pressure relief valve 43. The latter thereupon provides an increased opposing pressure in the governor 29, and the latter moves the admission valve 14 in opening direction.

The additional steam held back at the valve 26 and the additional steam admitted by the admission valve 14 supplies the additional high-pressure extracted fluid to the opening 15. The decrease in power development in the intermediate-pressure section 21 and the low-pressure section 22 is balanced by the increase in power development in the high-pressure section 19. The closing movement of the valve 28 effects a decrease in flow to the low-pressure section 22 equal to the decrease in flow through the valve 26, so that the amount of extracted fluid supplied to the opening 17 remains constant.

Upon decrease in demand for high-pressure extracted fluid, the pressure thereof increases and the parts of the control mechanism each move in the opposite direction. The flow through the high-pressure section 19 is decreased, and the flow through the intermediate-pressure section 21 and the low-pressure section 22 is increased.

Assume now an increase in demand for low-pressure extracted fluid, with the demand for high-pressure extracted fluid and the load on the turbine remaining constant. This operation is pictured in Fig. 5. The lever 57 remains stationary. The pressure of the fluid flowing through the opening 17 and the conduit 18 decreases, which decrease is communicated through the conduit 63 to the diaphragm 62. The lever 64 is tilted in counter-clockwise direction by the spring 67 an amount corresponding to the decrease. The arm 75 moves the arm 73 to the left, rotating the lever 69 in clockwise direction. The lever arm 72 moves upwardly and the pressure relief valve 45 provides decreased

opposing pressure in the governor 32. The latter moves the valve 28 in closing direction to hold back additional fluid from the low-pressure section 22.

5 The downward movement of the lever arm 71 controls the pressure relief valve 44 to provide increased opposing pressure in the governor 31, and the latter effects increased opening of the valve 26.

10 The upward movement of the right-hand end of the lever 64 effects upward movement of the left-hand end of the floating lever 76, the right-hand end being held stationary by the link 77. The lever 79 is tilted in clockwise direction, through the link 78, producing downward movement of the stem 52 of the pressure relief valve 43. The latter effects increased opposing pressure in the governor 29, which in turn effects increased 15 opening of the admission valve 14.

15 The increased openings of the valves 14 and 26 are such as to provide equal increases in flow through the high-pressure section and the intermediate-pressure section 21. This increased flow, together with the additional steam held back by the valve 28, supplies the increased demand for low-pressure extracted fluid. Said increase in flow is so related to the steam held back by the valve 28 that the 20 decrease in power development by the low-pressure section 22 is balanced by the increase in power development by the high-pressure section 19 and the intermediate-pressure section 21.

25 Upon decrease in demand for low-pressure extracted fluid, the pressure thereof increases and the parts move in opposite directions. The flow through the high-pressure section 19 and the intermediate-pressure section 21 is decreased and the flow through the low-pressure section 22 is increased. The decrease in power development by the first two-mentioned sections is balanced by the increase in power development by the low-pressure section 22.

30 It is to be understood that a simultaneous change in pressure at both of the openings 15 and 17 effects a resultant change in the positions of the various levers which is exactly the same as if the changes in pressure had occurred successively, producing first one, and then another of the operations described above.

35 The relations of changes in flow effected by the above-described operations are effected by properly proportioning the dimensions of the valves 14, 26 and 28, the diameters of the pistons 34 and the scales of the springs 37 in the governors, the scales of the pressure relief valves, the various lever arm ratios, the scales of the springs 61 and 67 and the diameters of the diaphragms 55 and 62. The determination of these relations involves only mathematical calculations and can be determined by one skilled in the art.

In order to adapt the control mechanism so that it may be readily applied to various operating conditions, I preferably provide a group or series of pivot openings in each of the levers 69, 76 and 79 and the lever arm 75. The pivot 68 of the lever 57 is preferably carried by a separate piece 68' secured to the lever by pins extending through openings 57' in the lever 57. In order to vary the location of the piece 68' on the lever 57, a series of 75 openings 57' is provided.

Suitable forms of adjustment may be employed throughout the control mechanism. For example, as shown in Fig. 2, each stem 52 may be adjustably secured to its lever by 80 a block 88, which is screw threaded on the stem and held in place by a lock nut 89. The block 88 carries pivot pins 91 extending through openings in links 92, which are pivoted at their upper ends to the attached lever, 85 for example, the lever 79. By turning the stem 52 in the block 88, the pressure relief valve may be adjusted to provide any desired pressure, within limits of adjustment, for a given position of the lever.

90 It will be apparent that the pressure within the region enclosed by an extraction pressure stage and the opening and extraction conduit communicating therewith is substantially the same, or at least varies similarly 95 with changes in demand, and that the pressure for controlling the associated pressure-responsive diaphragm may be taken at any point within that region.

95 Either or both of the openings 15 and 17 100 may be utilized to admit motive fluid of suitable pressure to the corresponding stages instead of extracting fluid therefrom. The operation of the parts is exactly the same, although possibly the pressure setting might 105 be slightly changed by adjusting the initial setting of the corresponding spring 61 or 67.

110 Assuming, for example, admission of motive fluid through the opening 15, an increase in supply would be accomplished by an increase in pressure imposed on the diaphragm 55. Such increase in pressure would operate, as above described, to effect increased opening of the valves 26 and 28 and decreased opening of the admission valve 14. The additional motive fluid admitted through the opening 15 would be utilized in the intermediate pressure 21 and the low-pressure section 22, requiring a decreased admission of high-pressure motive fluid by the admission valve 14.

115 Likewise, motive fluid at a pressure suitable for use in the low pressure section 22 may be admitted through the opening 17. 120 The control mechanism operates in the same manner as when fluid is extracted through the opening 17, the valve 28 moving in opening direction with increase in supply and pressure of fluid for the low pressure section 125 130

and the valves 14 and 26 moving in closing direction to maintain the proper load.

Upon decrease in supply and pressure of fluid admitted through either opening 15 or 17, the operation is in the reverse direction.

In Fig. 3, I show an embodiment of my control mechanism involving a modified arrangement of levers for controlling the pressure relief valves. Inasmuch as the parts other than the levers are constructed and function in the same manner as the parts of Fig. 1, they are referred to by the same reference numerals and are not described in detail.

The diaphragms 55 and 62, subjected to the high-pressure and low-pressure extracted fluid pressures, are connected to levers 57a and 64a, respectively. The latter are connected, through links 82 and 83, to a floating lever 84. The pressure relief valve 44 is connected to the lever 84 on the side of the link 82 remote from the link 83. The pressure relief valve 45 is connected to the lever 84 between the links 82 and 83.

The pressure relief valve 43 is connected to the lever 84 at a point between the links 82 and 83 by means of a link 85 and a lever 86 pivoted to a stationary fulcrum at 87.

The operation of this embodiment in response to changes in load and speed is as follows:

Assuming a constant load and constant demand for low-pressure extracted fluid, an increase in pressure on the diaphragm 55, occasioned by a decrease in demand for high-pressure extracted fluid, moves the lever 57a in clockwise direction. The levers move from the full line positions to the dotted line positions shown in Fig. 6, the lever 64a remaining stationary. The lever 84 is moved downwardly about the link 83 as a fulcrum. The stems 52 of the pressure relief valves 44 and 45 are moved downwardly to provide increased opposing fluid pressures in the governors 31 and 32, the latter operating to provide increased opening of the valves 26 and 28. The movement of the lever 84, transmitted through the link 85 and the lever 86, results in upward movement of the stem 52 in the pressure relief valve 43. The latter provides a decreased opposing pressure in the governor 29, which effects decreased opening of the admission valve 14.

Upon decrease in pressure on the diaphragm 55, the parts operate in the opposite direction as will be apparent.

Upon increase in pressure of the low-pressure extracted fluid, the diaphragm 62 moves the lever 64a in clockwise direction. The levers move from the full line positions to the dotted line positions shown in Fig. 7, the lever 57a remaining stationary. The lever 84 is tilted about the link 82, the stem of the pressure relief valve 44 being moved upward-

ly and the stem of the pressure relief valve 45 being moved downwardly. The stem 52 of the pressure relief valve 43 is also moved upwardly. The pressure relief valves 43 and 44 provide decreased opposing pressures in the governors 29 and 31, resulting in decreased opening of the valves 14 and 26.

The pressure relief valve 45 provides increased opposing pressure in the governor 32, resulting in opening movement of the valve 28. The flow through the high-pressure and intermediate-pressure sections is decreased and the flow through the low pressure section is increased, thereby decreasing the flow to the conduit 18 and maintaining the load on the turbine. Upon decrease in pressure on the diaphragm 55, each of the parts moves in the opposite direction.

It will be noted that the opposing fluid pressure imposed on each governor of either embodiment is increased in response to increase in pressure at any opening on the upstream or high-pressure side of the associated valve and that it is decreased upon decrease in pressure at any such opening. The opposing pressure is decreased by increased pressure at any opening on the low-pressure or down-stream side of the associated valve, and it is increased upon decrease in pressure at any such opening.

For the purpose of assisting in reading certain of the claims on the drawings, the opposing fluid pressures in the conduits 46, 47, and 48 have been designated first, second, and third fluid pressures, respectively. It will be noted that the movements of the pressure-responsive diaphragms 55 and 62 are in the same direction to effect change in a given direction in the first fluid pressure. For example, upward movement of the diaphragm 55 in response to increase in pressure at the opening 15 effects decrease in the first fluid pressure, and the movement of the pressure-responsive diaphragm is the same, that is, upward in response to increase in pressure at the opening 17, to effect decrease in the first fluid pressure. The pressure responsive diaphragms 55 and 62 move in opposite directions, that is, one moves in response to an increase in pressure and the other moves in response to a decrease in pressure, to effect change in a given direction in the second fluid pressure. Change in a given direction in the third fluid pressure is provided by movements of the pressure responsive elements in the same direction.

While I have shown my invention in two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. The combination with a multi-stage prime mover having admission valve means, means providing communication between the exterior of the prime mover and a plurality of intermediate pressure stages and a valve means controlling the flow of motive fluid at each of said intermediate pressure stages, of a regulating mechanism for each of said last-mentioned valve means comprising means providing a fluid pressure varying in consequence of variations in demand for flow through either of the communicating means and means responsive to said fluid pressure for controlling the valve means.

2. The combination with a multistage prime mover having admission valve means, openings communicating with a plurality of intermediate pressure stages, respectively, and the outside of the prime mover, a valve means controlling the flow of motive fluid at each of said intermediate pressure stages, of a regulating mechanism for each of said last-mentioned valve means comprising means providing a fluid pressure varying in response to variations in pressure in either of said openings, and means responsive to said fluid pressure for controlling the valve means.

3. The combination with a multi-stage prime mover having admission valve means, means providing communication between the exterior of the prime mover and a plurality of intermediate pressure stages and a valve means controlling the flow of motive fluid at each of said intermediate pressure stages, of a regulating mechanism for each of the valve means including a pressure-responsive controlling element and means for applying to the pressure-responsive controlling element a fluid pressure varying in consequence of variations in demand for flow through each of the communicating means.

4. The combination with a multistage prime mover having admission valve means, openings communicating with a plurality of intermediate pressure stages, respectively, a valve means controlling the flow of motive fluid at each of said intermediate pressure stages, of a regulating mechanism for each of the valve means including a pressure responsive controlling element, and means for applying to the pressure responsive controlling element a fluid pressure varying in response to variations in pressure in each of said openings.

5. The combination with a multi-stage elastic fluid prime mover having openings communicating respectively with a plurality of pressure stages therein, valve means controlling the admission of motive fluid to the prime mover and a valve means controlling the flow of fluid at each of said openings, of means associated with each of the valve means for regulating the same comprising means providing a fluid pressure which va-

ries in one direction in response to increase in pressure at an opening on the high-pressure side of the valve means and decrease in pressure at an opening on the low-pressure side of the valve means and which varies in 70 the opposite direction in response to decrease in pressure at an opening on the high-pressure side of the valve means and increase in pressure at an opening on the low-pressure side of the valve means, and means responsive to said fluid pressure for controlling the valve means.

6. The combination with an elastic fluid prime mover having a high-pressure section, an intermediate-pressure section, a low-pressure section, and an opening between the high-pressure and intermediate-pressure sections and an opening between the intermediate-pressure and low-pressure sections for admitting or discharging motive fluid, of 80 means providing a fluid pressure which varies in one direction in response to increase in pressure of motive fluid at the first-mentioned opening and in the opposite direction in response to increase in pressure at the 90 second-mentioned opening, means responsive to said fluid pressure for controlling the flow of motive fluid to the intermediate-pressure section, means providing a second fluid pressure which varies in one direction in response to increase in pressure of motive fluid at the first-mentioned opening and in the same direction in response to increase in pressure at the second-mentioned opening, and means responsive to said second fluid pressure for 100 controlling the flow of motive fluid to the low-pressure section.

7. The combination with a prime mover having a high-pressure section, an intermediate pressure section, a low-pressure section, 105 a first opening between the high-pressure and intermediate-pressure sections and a second opening between the intermediate-pressure and low-pressure sections for admitting or discharging motive fluid, of means providing 110 a first, a second, and a third fluid pressure each varying in response to the changes in pressure at said openings, the changes in pressure at said openings being in the same direction, relative to each other, for providing variation in a given direction in the first fluid pressure, in the opposite direction, relative to each other, for providing variation in a given direction in the second fluid pressure, and in the same direction, relative to 115 each other, for providing variation in a given direction in the third fluid pressure, and means for controlling the flow of fluid to the high-pressure section, the intermediate pressure section and the low-pressure section in response to the first, the second, and the third fluid pressure, respectively.

8. The combination with a multi-stage elastic fluid prime mover having openings 120 communicating with two pressure stages

therein, respectively, and the outside of the prime mover, valve means controlling the admission to the prime mover and a valve means controlling the flow of fluid at each of said openings, of a control mechanism comprising two pressure-responsive elements each subjected to the pressure at one of said openings, means controlled by said pressure-responsive elements for providing a first, 5 a second, and a third fluid pressure, the movements of the pressure-responsive elements being in the same direction, with respect to each other, to provide a change in a given direction of the first fluid pressure, the movements of the pressure-responsive elements 10 being in the opposite direction, with respect to each other, to provide a change in a given direction in the second fluid pressure, the movements of the pressure-responsive elements 15 being in the same direction, with respect to each other, to provide a change in a given direction in the third fluid pressure, and means for operating the admission valve means, the valve means at the stage of higher 20 pressure and the valve means at the stage of lower pressure in response to the first, the second and the third fluid pressure, respectively.

9. The combination defined in claim 8 and 25 further comprising means providing a fluid pressure varying as a function of the speed of the prime mover and wherein the valve means are also operated in response to said last-mentioned fluid pressure.

30 35 In testimony whereof, I have hereunto subscribed my name this 26th day of June, 1930.
